UNITED STATES PATENT OFFICE.

WILLIS LUTHER MOORE, OF PASADENA, CALIFORNIA.

VENTILATING SYSTEM.

Application filed November 5, 1925. Serial No. 66,938.

My invention relates to a ventilating system for houses and other buildings in which natural air currents are utilized in producing a positive ventilation of rooms in the building.

It is an object of this invention to provide a simple, economical, efficient ventilating system for houses and the like, which will not detract from the outward appearance thereof, whereby air will be caused to flow positively into rooms to be ventilated and where the same air currents are utilized in causing a flow of exhaust air from the rooms to the outer air. The apparatus functions automatically, irrespective of the direction of the wind.

With the above and other objects in view, which will appear as the description proceeds, my invention consists in the arrangement and combination of parts, hereinafter described and claimed.

Referring to the drawings, which form a part of the specification:

Figure 1 is a horizontal cross-section taken on line 1—1 of Fig. 2;

Fig. 2 is a vertical cross section of a house equipped with my ventilating apparatus;

Figs. 3 and 4 are detailed views showing ventilating louvers in open and closed position.

Referring to the drawings, 1 represents a building such as a house having rooms 2 and 3. Intermediate the top and bottom of the roof 4 I provide what I term an air gatherer 5, consisting of a horizontal bottom partition 6 and a top plate 7, the latter tapering downwardly towards the center. A series of radial vertical partitions 8 divide the air gatherer 5 into a plurality of substantially horizontal chambers 9, which, as clearly shown in Figure 1, converge toward the center. The partition 6 adjacent the center of the air gatherer is curved downwardly at 10, which is substantially parallel with the portion of the top 7 immediately above. The object of this construction is to give the air current flowing toward the center a downward direction. To prevent any eddying or cross current at the inner end of the chamber 9 I provide a series of parallel air direction plates 11, which are substantially parallel to the top 7 and the floor 10 immediately above and below.

A cylindrical valve 12, vertically arranged, is provided with an air inlet port 13 adapted to register with one or more of

chambers 9. The port 13, as shown in Figure 1, is of dimensions to register with the outlet ports of two adjacent chambers 9. Roller bearings 14 on cylindrical valve 12 are provided to eliminate friction as far as possible and insure proper functioning of the cylinder valve 12 by means of the weather vane 15 secured to the top thereof. The air passes from the cylindrical valve 12 downwardly through an air purifying and moistening device 16 of any desired or preferred construction. The same forms no part of the present invention, and may be omitted altogether and the air may be passed directly through conduits 17 provided with valves 18 to chambers 2 and 3 of the house. Air exhaust ports 19 are provided in rooms 2 and 3, through which the exhaust air passes through the roof chamber 20 formed by the roof 4, partition 6 of the air gatherer and the ceilings of the rooms 2 and 3, thence the air passes out into the atmosphere through exhaust stacks 21, of which I have shown four in number, preferably disposed at the corners of the air gatherer 5. The air inlet ports 18 in the rooms 2 and 3 are preferably provided with manually operated valves 18' to regulate the fresh air supply.

In order to facilitate the movement of the exhaust air and to insure positive flow of air current, I provide on the sides of the house, between the ceilings of the rooms and the roof 4, a series of louvers 22, which are made adjustable, as shown in Figs. 3 and 4, and may be operated by any suitable mechanism, not shown, attached to operating rod 23.

The apparatus functions as follows:

Assuming that there is a slight breeze or current of air coming in the direction indicated by the weather vane 15, shown in Fig. 2, the same will enter air chambers exposed to that direction. It should be noted here that the upper roof section 4' above the air gatherer 5 is off set in regard to the lower roof section 4" below the air gatherer 5, so that as the air current strikes the lower roof section 4" and is deflected upwardly, it will flow along the roof until it strikes the openings of air chambers 9 and then will flow toward the center. Owing to the construction of the air chambers 9, which are wide at the entrance but gradually converge toward the center, the velocity of the air current is increased as the air moves inwardly. The air is given a downward direction, due

to the downward curvature at 10 of the air chambers 9 assisted by deflector plates 11, and enters the port 13. The port 13 registers with the said chambers 9 by reason of the 5 position of the weather vane 15 which turns the port 13 always in the direction of the wind. The air passes through the air washer and purifier 16, which, however, as stated before, may be omitted, thence through air 10 conduits 17 into the rooms 2 and 3 below. The exhaust air leaves the rooms 2 and 3 through outlet ports 19 into the roof chamber 20, whence the air passes through the exhaust stacks 21 into the atmosphere. The 15 movement or current of air through the roof chamber 20 and out through the exhaust stack 21, is assisted by the wind, which passes through the open louvers 22 and creates a draft through the exhaust stacks 21. 20 Louvers 22 are adjustable, and the louvers on the sides of the house, not in the direction of the wind, may be closed or partially closed, to produce the proper draft.

It is thus seen that I have constructed an 25 automatic ventilating system which is effective irrespective of the direction of the wind, and which produces a positive ventilation of the rooms of the building, provision being made to accelerate the speed of the air current downwardly and deflect the same downwardly into the rooms of the building, and also means being provided to assist in the 30 exhaust of the said rooms. It should also be noted that the apparatus as installed in the 35 house does not detract from the appearance thereof, the major part of the apparatus being within the roof chamber, which usually is a vacant or waste chamber.

Various changes may be made in the arrangement and construction of parts by those 40 skilled in the art, without departing from the spirit of my invention, as claimed.

I claim:

1. In a ventilating system for rooms of 45 buildings, comprising the combination of a substantially horizontal air gatherer open on all sides and disposed intermediate the top and the bottom of a roof of a building, said air gatherer being divided into a series 50 of radial air chambers, each chamber having its walls converging downwardly and

toward the center of said air gatherer, an air conduit leading from the inner ends of said radial air chambers to a room below, a wind controlled valve directing the air 55 from said air chambers to said air conduit, an air exhaust chamber below said air gatherer and an air exhaust port leading from said room to said air exhaust chamber, a series of exhaust stacks conveying the air from said air exhaust chamber to the atmosphere, and adjustable louvers in the sides of said air exhaust chamber to regulate the admission of air from the atmosphere to the said air exhaust chamber. 60 65

2. In a ventilating system for rooms of buildings comprising the combination of a horizontal air gatherer open on all sides and disposed intermediate the top and the bottom of a roof of a building, said air gatherer being divided into a series of radial air chambers having means at the inner ends for deflecting the air downwardly, an air conduit for passing the air from the air chambers to a room below, a wind controlled valve 70 75 directing the air from said air chambers to said air conduit, an air exhaust chamber below said air gatherer and an exhaust port leading from said room to said air exhaust chamber and an exhaust stack conveying the air from said air exhaust chamber to the atmosphere. 80

3. In a ventilating system for rooms of buildings comprising the combination of an air gatherer on the roof of a building, said air gatherer being divided into a series of radial air chambers having means to deflect air downwardly, an air conduit communicating with said air chambers leading the air into a room below, a wind controlled 90 95 valve controlling the passage of air from the said air chambers to said air conduit, an air exhaust chamber above said room communicating therewith, a stack conveying air from said exhaust chamber to the atmosphere and controllable means for admitting outside air into said air exhaust chamber to assist the draft in said exhaust stack.

In testimony whereof I have signed my name to this specification.

WILLIS LUTHER MOORE.
